[57] CLAIM

The ornamental design for an appliance housing, as shown and described.

DESCRIPTION

FIG. 1 is a front and left side perspective view of an appliance housing showing my new design;
FIG. 2 is a front elevational view;
FIG. 3 is a rear elevational view;
FIG. 4 is a left side elevational view, the right side elevational view being a mirror image thereof;
FIG. 5 is a top plan view; and
FIG. 6 is a bottom plan view thereof.
